SHIP CARGO RIG

Clifford M. Pedersen, San Francisco, and Shirley L. Morgan, Sausalito, Calif.

Application September 15, 1943, Serial No. 502,420

2 Claims. (Cl. 212—3)

The present invention relates to ship's cargo hoist rigs of the type employed in loading and unloading operations.

One of the objects of this invention is to provide a simplified hoisting rig which will utilize conventional deck installations of booms and winches and effect certain economies of operation as well as greatly speed up the cargo handling operations.

It is a well known fact that the tempo of the present world war dictates that speed is of the essence and this is particularly true in the transportation of cargo by ship. Acceleration of cargo handling while war inspired is susceptible of peacetime application. It is therefore one of the primary objects of this invention to adapt the deck equipment presently employed to a simplified form of apparatus capable of increasing capacity in a substantial degree. Additionally, it is an object of this invention to provide an improved hoisting rig which will be easy to operate and thus avoid the necessity of prolonged instruction to operators trained along conventional lines.

In general terms the objects of this invention are attained through the use of two falls, one of which may be designated a power fall and the other of which may be termed the guide fall, which engage independent drum means for the raising, movement and lowering of cargo or slings of the same. Moreover, the invention contemplates that the guide fall carry at its free end a sheave or other direction changing means over which the power fall is passed to facilitate the load guiding operation.

It has been standard practice in handling ship's cargo to employ two power falls connected to independent winches, each passed over a boom-supported sheave and terminating in their respective common connections to a weighted sling hook or, as it is termed in maritime practice, the "blacksmith." When the blacksmith is lowered away into the ship's hold through the cargo hatch, both of the respective winches are reversed to slack the connected falls. In the raising operation, however, power is initially applied only to the winch actuating the first fall, namely, the fall on the boom over the hatch to raise the load clear of the hatch coaming while the slack of the companion, or second fall, is taken up by application of power to the winch to which it is connected.

When the load is clear of the hatch coaming, power is applied to the second fall to move the load laterally toward ship side while the power

on the first fall is slackened off. As the weight of the load passes through equilibrium between the two falls the full weight shifts from the first to the second fall and power must be exerted on the latter to sustain and lower the load to dock or lighter.

As a consequence of this conventional practice, it is necessary to employ two power winches for each sling hook or blacksmith despite the fact that fifty per cent of the time each of them is idle. In the present invention a single power winch will serve each unitary rig since the guide fall requires but a minimum of power and may therefore be actuated by drum or pulley auxiliary to the main winch drum.

In the accompanying drawings wherein preferred forms of the invention are shown as examples,

Figure 1 is a side elevation of a cargo rig operating from a single winch means, and

Figure 2 is a side elevation of a pair of the cargo rigs of Figure 1 working a single hatch with the aid of companion winches.

In the single rig form shown in Figure 1 the letter A designates the power or load sustaining fall, wound on the drum 10 of the winch 11 and passing through a direction changing sheave 12 anchored on the ship's deck 13. Fall A is next passed through a block 18 pivotally connected to a collar 19 adjacent the tip of boom 15, through sheave 20 at the free end of fall B, and terminating in its connection to a cargo hook 21. In lieu of the usual blacksmith a ball weight 22 is provided on fall A in proximity to hook 21.

Fall B is the guide fall having its inner end wound on pulley 25 on winch 11, passing through sheave 26 on deck 13, thence through block 27 at the foot of boom 28, block 29 at the tip of boom 28 and terminating in a swiveled connection to sheave 20.

In the form illustrated winch 11 may consist of a parallel pair of double ended steam driven pistons in the housing 35, operatively connected to the drum 10 and drum 25, and provided with independent controls 36 and 37, respectively. It will be understood that the particular form of the winch means is not critical as any type of winch equipped with a main power drum and an auxiliary pulley means, independently driven or engageable with the main winch by clutch means and provided with braking means, will serve to carry out the purpose of the invention.

Moreover, the invention contemplates that standard practices will be carried out in the guy rigging of the booms 15 and 28 for their support

and angular disposition as well as clearances for loads and the like, for which reason it is not deemed necessary to illustrate any particular guy rigging in the accompanying drawings.

The operation of the hoist rig illustrated in Figure 1 will be understood to be as follows:

Assuming the hook 21 to be disposed, as shown, directly above the hatch, the operator by reversing the control lever 36 slacks off on the power fall A to lower the hook into the ship's hold. During this operation control lever 37 is set in neutral position which holds sheave 20 in fixed or stationary position permitting the free run of fall A. When a load has been secured on hook 21, control 36 is set in its forward or takeup position and thus power is applied to fall A to raise the load vertically. When the load has been raised to a satisfactory height in relation to the hatch coaming, control lever 36 is returned to neutral position thus holding the load above the hatch. Control lever 37 is then set in its forward or takeup position to draw fall B and the sheave 20 carried thereby toward boom 28 and shipside. Simultaneously control lever 36 is set at reverse position to slack off fall A consistently with the speed of movement of the load in the direction of shipside. It will be understood, of course, that boom 28 will be disposed at sufficient angle to project beyond shipside so that a load suspended therefrom will clear for deposit on dock or lighter. When the takeup on fall B has moved sheave 20 sufficiently toward boom 28 to permit the load to clear shipside, control lever 37 is returned to neutral position and sheave 20 is thereby held in fixed relation to boom 28 as though secured thereto. Continuing slackening off of fall A will permit proper deposit of the load.

In the double rig illustrated in Figure 2 of the drawings, it will be noted that we contemplate the use of power falls A and C and guide falls B and D. Similarly, we employ the companion winches 41 and 42, corresponding to the single winch 11 of Figure 1.

In this modification power fall A is passed over pulley 43 collared adjacent the top of boom 15, thence through the pulley 44 at the foot of the said boom, through the direction changing block 45 and is wound on the drum 46 of winch 42. Guide fall B passes over pulley 49 collared adjacent the top of boom 28, thence over pulley 50 at the foot of said boom, through the direction changing block 51 and is wound on the drum 52 of winch 42.

Oppositely, power fall C is passed over a pulley 56 fixed at the top of boom 28, thence through pulley 57 at the foot of the said boom, through the direction changing block 58 for winding on the drum 59 of winch 41. The companion or guide fall D is passed over pulley 62 disposed at the top of boom 15 thence through pulley 63 at the foot of said boom, through the direction changing block 64 for winding on drum 65 of winch 41.

It will be appreciated, of course, that the winches 41 and 42 are provided with the dual controls 36 and 37 as in the case of the winch 11. Likewise, it will be understood that each of the power falls, A and C, are equipped with ball weights 22 and cargo hooks 21 and that said

falls pass through the direction changing sheaves 20 at the ends of the respective guide falls B and D, respectively.

The companion rigs are equipped in the manner of the single rig of Figure 1 in that pulleys 20 are disposed at the free ends of guide falls B and D while power falls A and C are each provided with ball weights 21 and cargo hooks 20.

In operation, the double rig contemplates the by-passing of the cargo hooks disposed at the ends of the falls A and C. In an unloading operation and as illustrated in Figure 2, hook 21 on power fall A is raising a box 10 and having cleared the hatch, control lever 36 of winch 42 will be set in reverse position to slack off on power fall A as guide fall B is wound on drum 52 sufficiently to draw the cargo 10 in the direction of boom 28 to clear shipside where it may be lowered away.

Meanwhile, control lever 37 of winch 41 may be set in its forward or takeup position to pull guide fall D over the hatch while lever 36 of winch 41 is positioned to slack off on power fall C to lower the hook 21 carried thereby into the hold for loading.

Obviously the loading or unloading operation from a single hatch can be materially speeded up through the use of the double hook rig in Figure 2 of the drawings. What is more, by utilizing the novel features of our invention with the conventional installation of twin winches at each hatch, the speed-up of loading can be achieved at a minimum cost.

While, as illustrated, drums 10 and 25 of winch 11 (Fig. 1) and drums 46 and 52 of winch 42 and drums 65 and 59 of winch 41 (Fig. 2) are shown as positively driven by common shafts, the rotation of which is controlled by levers 36 and 37, it will be understood that it is within the purview of our invention to substitute conventional clutch and backing means in connection with the drums 25, 52 and 65, respectively, to permit taking up or slackening off of the guide falls independently of the application of power to power falls A and C.

Having thus shown and described our invention, what we desire to secure by grant of Letters Patent is:

1. A ship cargo rig comprising, a power fall, a guide fall, a sheave connection between the operative end of the guide fall and the power fall, boom means providing separate elevated support for the said power and guide falls, pulley blocks on the boom means to effect change of direction of the respective falls, and winch means for selectively taking up or slackening off the respective power and guide falls.

2. A ship cargo rig comprising, a pair of power falls, a pair of guide falls, sheave means disposed at the operative ends of each of the respective guide falls providing a running connection for each of the power falls, boom means providing a common elevated support for a power fall and a guide fall, pulley blocks on the boom means to effect change of direction of the respective falls, and winch means for selectively taking up or slackening off the respective power and guide falls.
